United States Patent Office

Des. 189,709
Patented Jan. 31, 1961

189,709

ANCHOR

Frederick P. Dickow, Auburn, N.Y., assignor to Eastern
Malleable Iron Co., Naugatuck, Conn., a corporation
of Connecticut

Filed Dec. 23, 1959, Ser. No. 58,777

Term of patent 14 years

(Cl. D71—1)

FIG. 1

FIG. 2

Figure 1 is a front elevational view of an anchor showing my new design;

Figure 2 is a bottom plan view thereof;

Figure 3 is a side elevational view thereof;

Figure 4 is a fragmentary sectional view taken on the line 4-4 of Figure 2; and

Figure 5 is a fragmentary sectional view taken on the line 5-5 of Figure 1;

I claim:

The ornamental design for an anchor, substantially as shown.
